UNITED STATES PATENT OFFICE.

VALENTINE S. PERAZIO, OF NEW YORK, N. Y.

FRUIT CRUSHER AND SQUEEZER.

Application filed December 29, 1926. Serial No. 157,741.

This invention relates to fruit crushers and squeezers and has for an object to provide an improved simplified structure which may be operated by power or by hand and which has a simple arrangement for receiving the fruit at one point, discharging the juice at a second point and the pulp at a third point.

Another object of the invention is to provide a fruit crusher and squeezer wherein a pair of rotatable crushing and squeezing members is utilized and arranged to provide a continuous crushing and squeezing action during the operation of the device.

A further object, more specifically, is to provide in a fruit crusher and squeezer a substantially floating squeezing roller or wheel associated with means for varying the squeezing tension of the roller.

In the accompanying drawings—

Figure 1 is a side view of a fruit crusher and squeezer disclosing an embodiment of the invention.

Figure 2 is an edge view of the structure shown in Figure 1.

Figure 3 is a sectional view through Figure 2 on line 3—3.

Figure 4 is a sectional view through Figure 1 on line 4—4.

Referring to the accompanying drawings by numerals, 1 indicates legs or supports of any desired kind, said legs or supports being connected to a pair of side plates 2 and 3, said side plates at the rear being connected by suitable spacing plates 4 riveted or otherwise secured to the side plates. The plates 2 and 3 are also connected together by any desired number of bolts 5 having reduced ends extending through the plates and threaded for receiving suitable clamping nuts 6. The bolts 5 in addition to holding the side plates 2 and 3 in proper position, act as guiding means or bearings for a crushing ring 7. The crushing ring 7 is provided with a raised portion 8 centrally thereof as shown in Figure 2, said raised portion being straddled by a supporting roller 9. The roller 9 is rotatably supported on a bolt 10.

In operation, most of the pressure is supported by the roller 9 while the various bolts 5 somewhat support and guide the ring. This ring slidingly engages the side plates 2 and 3, the contact being sufficient to prevent the pulp from coming through but ample space is allowed for the flow of liquid as indicated in Figure 2, said liquid being caught

by a suitable inclined pan or trough 12. Gear wheels 13 and 14 are formed integral with ring 7 or rigidly secured thereto and continually mesh with the pinions 15 and 16, said pinions being rigidly secured to a shaft 17. A hand wheel 18 is also secured to shaft 17, said hand wheel carrying a grip 19 whereby the hand wheel may be freely rotated and, consequently, the pinions 15 and 16 rotated which will cause a rotation of ring 7. Preferably the device is made comparatively small and is usually to be hand operated so that the wheel 18 is used. If desired, however, power means could be connected to shaft 17 and the device driven by power. Ring 7 on the interior is preferably smooth except for a number of teeth 20, each alternate tooth 20 being longer than the other teeth so as to assist in breaking up or crushing the fruit as it approaches the squeezing point.

As indicated in Figure 3, a crushing and squeezing roller 21 is mounted interiorly of ring 7 and coacts with the interior surface thereof in crushing and squeezing the fruit. The ends of the roller 21 bear lightly against the plates 2 and 3 while the periphery of the roller is provided with a number of teeth 22 coacting with teeth 20 for crushing the fruit. Under some circumstances, where there is only a small amount of fruit passing through the device these teeth will interlock on the order of gear teeth so that the roller 21 will be rotated as ring 7 is rotated. Roller 21 is mounted on the bearing shaft 23 which extends through suitable slots 24 in the side plates 2 and 3. The outer ends of the shaft 23 are carried by levers 25 and 26, said levers being substantially L-shaped as shown in Figures 1 and 3 and pivotally mounted by suitable pins 27 carried by the plates 2 and 3. The outer or free ends of the levers 25 and 26 are connected by a shaft 28 on which is pivotally mounted a tension rod 29. The tension rod 29 passes loosely through a bar 30 carried by the plates 2 and 3. A spring 31 surrounds rod 29, presses against bar 30 and against the tension nut 32 whereby the crushing and squeezing tension of roller 21 may be varied merely by turning the nut 22. Near the upper part of the ring 7 is arranged a discharge chute 33 secured to the side plates 2 and 3 by bolts or other suitable means. This discharge chute extends near the roller 21 to near the inner surface of ring 7 and acts to receive the pulp 34 and guide the same

to a point exteriorly of the machine. An inlet chute or hopper 35 is riveted or otherwise rigidly secured to the side plate 3 and discharges through the opening 36 into the lower part of the ring 7. In Figure 3, apples have been shown in the device but it will be evident that other fruit may be crushed in the device and may be fed into the device in a similar manner with the pulp passing out as indicated in Figure 3 and the liquid moving by gravity past the ring 7 into chute 12. It will be evident that the device may be rotated at almost any desired speed and that the fruit is first broken up somewhat by the teeth 20 and 22 and then it is further crushed and squeezed as it passes near the pinions 15 and 16 as the roller 21 and ring 7 are closest together at this point.

What I claim is:

1. In a fruit crusher and squeezer a rotatable ring, means for rotatably supporting the ring, means for loosely closing the sides of the ring, said ring having on the inner surface a plurality of teeth acting as crushing teeth and also gear teeth, means engaging the outer surface of the ring for rotating the

ring and a squeezing roller mounted within the ring provided with a plurality of crushing teeth acting as gear teeth when the squeezing roller is moved sufficiently near said ring to engage the teeth on the inner surface of the ring, and means for varying the position of the crushing roller in respect to the inner surface of said ring.

2. In a fruit crusher and squeezer a rotatable ring, a freely rotatable roller arranged within the ring, a lever structure for supporting the roller, a bell crank lever for swinging the roller toward and from the inner periphery of the ring so as to vary the squeezing action of the roller, means for pivotally mounting said bell crank lever, a pivotally mounted rod loosely extending through one end of said bell crank lever, a spring surrounding said rod and acting on said lever for resiliently urging said lever in one direction, a nut carried by said rod co-acting with said spring for varying the tension of the spring, and means engaging the outer surface of the ring for rotating the same.

VALENTINE S. PERAZIO.
